ARTHUR R. WEIS, OF HUNTINGTON PARK, CALIFORNIA, ASSIGNOR OF ONE-HALF TO PACIFIC PUMP WORKS, OF HUNTINGTON PARK, CALIFORNIA, A CORPORATION OF CALIFORNIA, AND ONE-FOURTH TO GEORGE E. BIGELOW, OF HUNTINGTON PARK, CALIFORNIA.

CENTRIFUGAL IMPELLER LOCKING THRUST ELIMINATING MEANS

Application filed April 30, 1928. Serial No. 273,879.

My invention relates to deep well turbine pumps and particularly to the construction of the pump bowls of such pumps.

In the type of deep well turbine pumps in common use, the pump includes a pump head located at the top of the well on the surface of the ground, a column pipe connected to and supported by the pump head, a pump section connected to the column pipe in the lower portion of the well, and a shaft extending through the column pipe from the pump head to the pump section.

The pump section usually comprises a plurality of pump bowls connected together end to end. There is provided a continuous passage through the pump section connecting the impeller chambers, one of which is formed in each pump bowl. Positioned in each impeller chamber is an impeller which is non-rotatably secured to the shaft. When the shaft is rotated by the pump head the impellers are caused to rotate, thus centrifugally impelling the well fluid upward through the continuous passage through the pump section into the column pipe and thence to the surface of the ground.

Heretofore, the impellers have usually been secured to the impeller or pump shaft by a Woodruff or gib head key. I have sometimes found the keys and the key-ways in the shaft and impeller hubs inaccurately formed so that the impellers when keyed to the shaft were not in axial alignment therewith. When the impeller is thus cocked on the shaft the rotating assembly is thrown out of balance and the life of the pump is thereby shortened.

It is an object of my invention to provide a means for securing an impeller to a pump shaft so that they will be in axial alignment.

Furthermore, I have found that the cutting of key-ways in a pump shaft many times causes warping of the shaft with a consequent whipping action during operation. This whipping action oftentimes causes crystallization and fracture of the pump shaft.

It is correspondingly an object of my invention to provide a means for securing an impeller to a pump shaft which will not require key-ways in the shaft.

In that construction of a pump section in which the impeller is secured to the pump shaft by a key, the hub of the impeller is necessarily of considerable thickness in order to provide sufficient material to permit the cutting of a keyway. This requires that the lower end of the impeller hub be of a relatively large diameter so that in such constructions the central passage through the impeller is materially restricted. Since the casings in which deep well turbine pumps have to be installed impose a severe spacial limitation upon the pump design, that construction which further limits the design by restricting the central passage of the impeller is obviously undesirable.

It is therefore an object of my invention to provide a means for securing an impeller to a pump shaft which will eliminate the necessity of the impeller hub being of a large diameter and extending into the central passage of the impeller, and which will thereby permit an increase in the size of the central impeller passage.

It is common practice in securing an impeller to a pump shaft to use a gib head key with its head disposed downward and supporting the impeller in proper position in the impeller chamber by engagement with the lower end of its hub. In such an assembly the head of the key projects below the hub of the impeller into the central passage of the impeller. I have found that such a projection in the impeller passageway at the high rate of speed at which the impeller rotates causes cross-currents and disturbances which materially decrease the efficiency of the pump.

It is a further object of my invention to provide a means for securing an impeller to a pump shaft which will have no irregular projections extending into the fluid passageway.

In an attempt to eliminate the evils consequent to the use of the gib head key, as outlined above, the impellers have sometimes been non-rotatably secured to the shaft by feather keys and properly spaced by thin tubular sleeves surrounding the pump shaft between the impellers. In such a construction the entire assembly is forced against a

shoulder formed on the pump shaft about the uppermost impeller by the application of a nut to the lower end of the shaft. Besides being objectionable as including keyways in the shaft for the reasons outlined above, such an assembly is very expensive. Moreover, the thin tubular sleeves are exposed to the streams of well fluid carrying sand and other abrasive materials at a high rate of speed, and have been known to be cut through by this abrasive action so that the impellers were permitted to drag on the walls of the impeller chamber, thus completely destroying the pump.

It is a still further object of my invention to provide a means for securing an impeller to a pump shaft which will prevent axial displacement of the impeller relative to the pump shaft and which will not be rendered 10 inoperative by the abrasive action of the pump fluid.

In the operation of a centrifugal turbine pump there is exerted by the well fluid a greater downward force on the upper shroud 25 of the impeller than on the lower shroud. This excess of pressure on the upper shroud over that on the lower shroud materially increases the axial thrust on the bearings and is therefore objectionable.

It is an object of my invention to provide a means for attaching an impeller to a pump shaft which will make the pressure on the upper shroud equal to, or nearly equal to, the pressure on the lower shroud of the impeller.

It is a still further object of my invention to provide a means for attaching an impeller to the pump shaft in which any pressure on the upper shroud in excess of the pressure 40 on the lower shroud of the impeller will make the attachment of the impeller to the pump shaft more secure.

It is another object of this invention to provide a means, as above described, which 45 will be rugged in construction and simple in operation.

The novel fastening means of my invention finds utility in other capacities than in the deep-well turbine art, and my invention thus broadly comprehends a novel device for securing two elements together, whether or not these elements comprise an impeller and a pump shaft.

Still a further object of this invention is to provide a novel impeller construction.

Further objects and advantages will be made evident in the following description and the accompanying drawing, in which,—

Fig. 1 is a diagrammatic view illustrating the installation of a pump embodying my invention in a deep well.

Fig. 2 is an enlarged fragmentary vertical sectional view illustrating the construction 65 of a pump section embodying my invention.

Fig. 3 is a horizontal sectional view taken on the line 3—3 of Fig. 2.

Referring to the drawing and particularly to Fig. 1, the numeral 11 represents a well 70 in which a casing 12 has been extended to a water bearing stratum 13. Supported at the surface of the ground and extending downwardly in the well casing 12 is a column pipe 14 connected at its lower end to a pump section 15. Extending through the length of the column pipe 14 is a shaft tube 16 in which there is journalled by suitable bearings a line shaft 17. The line shaft 17 is supported and driven by a pump head 18 at the surface of the ground. The lower portion of the line shaft 17 extends through the pump section 15 so that by rotation of the line shaft 17 the pump section 15 is caused to force well fluid from the stratum 13 upward through the column pipe 14 to the surface of the ground. 80

The pump section 15 includes an upper main bearing 19, which is attached to the lower end of the column pipe 14, and a plurality of impeller bowls 20 connected together 90 end to end, the uppermost impeller bowl being attached to the upper main bearing 19. The lowermost of the impeller bowls 20 is connected to a lower main bearing 21 which supports a screen pipe 22 through which the well fluid enters the pump section. Each 95 impeller bowl 20 provides an impeller chamber 23 and fluid passages 24 connecting the outer portion of each impeller chamber 23 with the central portion of the impeller chamber in the adjacent upper impeller bowl. 100 Formed centrally through each impeller bowl 20 is a line shaft bore 25. Also centrally disposed in each impeller bowl 20 is a tapered bore 26 which, as clearly shown in Fig. 2, is divergent downward.

Disposed in each impeller chamber 23 is an impeller 27 which provides an upper shroud 28 and a lower shroud 29 connected by walls 30 to form radial passages 31. Connecting the radial passages 31 is a central 110 impeller passage 32.

Formed on each impeller 27 and extending upwardly into the tapered bore 26 of the impeller bowl 20 is a cylindrical hub 33. As 115 best shown in Fig. 2, there is formed in the hub 33 a central tapered bore 34 which is divergent downward.

The impeller securing means of my invention includes a sleeve structure 34a comprising a sleeve 35 having a longitudinal slot 41, best shown in Fig. 3. This sleeve structure has a central cylindrical bore 36 adapted to receive the line shaft 17. At the lower end of the cylindrical bore 36 is an inwardly projecting annular shoulder 37 which is adapted to be received in an annular groove 38 in the line shaft 17. As clearly shown in Fig. 2, the sleeve 35 comprises a lower portion 39 tapered to fit in the tapered bore 34 of the 130

impeller hub 33 and an upper externally threaded portion 40.

In assembling an impeller 27 upon the line shaft 17 before the impeller bowl 20 is in position, the impeller 27 is placed loosely upon the sleeve structure 34a and the sleeve structure 34a is then moved downwardly on the line shaft 17 until the shoulder 37 engages the annular groove 38 in the line shaft 17. The impeller 27 is then moved downwardly on the sleeve structure 34a by the pressure exerted on the top of the impeller hub 33 by a lock-nut 42 screwed on the externally threaded portion 40 of the sleeve 35. The slot 41 permits the contraction of the sleeve 35 about the line shaft 17 as the impeller hub 33 is moved downwardly on the sleeve structure 34a so that a tight frictional engagement is secured between the sleeve 35 and the line shaft 17. A tight frictional engagement is likewise secured between the sleeve 35 and the hub 33 of the impeller 27 by the nut 42 forcing the impeller 27 downward on the tapered portion 39 of the sleeve 35. It is evident that the engagement between the sleeve 35 and the impeller hub 33 retains the impeller 27 in axial alignment with the line shaft 17. The engagement of the shoulder 37 of the sleeve 35 with the annular groove 38 of the line shaft 17 retains the impellers 27 in proper axial position upon the line shaft 17 without the use of spacing tubes. Moreover, this construction eliminates the necessity of having the hub 33 of the impeller 27 extend into the central impeller passage 32, so that the central impeller passage is in no way restricted by the impeller hub.

This construction likewise eliminates the necessity of any irregular projections upon the impeller hub 33 or the sleeve 35 in the central impeller passage 32, so that the well fluid in the central impeller passage is not subjected to cross-currents or disturbances. The slot 41, besides permitting the contraction of the sleeve 35 about the line shaft 17 in assembling the impeller and expansion of the sleeve 35 when removing the impeller also permits the well fluid that may be present between the upper shroud 28 and the tapered bore 26 of the impeller bowl 20 easy communication with the well fluid in the central impeller passage 32.

This communication makes the pressure of the well fluid upon the upper shroud 28 equal to or but slightly greater than the pressure of the well fluid upon the lower shroud 29. By virtue of the downward divergence of the tapered portion 39 of the sleeve 35 and the tapered bore 34 of the impeller hub 33, any slight excess of pressure on the upper shroud 28 over that on the lower shroud 29 will increase the frictional engagement both between the impeller hub 33 and the sleeve 35, and between the sleeve 35 and the line shaft

17, so that the attachment of the impeller 27 to the line shaft 17 is rendered more secure. It is evident that neither the engagement of the sleeve 35 with the line shaft 17 nor the engagement of the impeller hub 33 with the sleeve 35 can be affected by the abrasive action of the well fluid, and it is therefore apparent that I have provided a means for securing an impeller to a pump shaft which will not be rendered inoperative by such abrasive action.

Although the form of embodiment of my invention herein illustrated and described is fully capable of performing all of the objects primarily stated, I do not wish to be restricted to this form, for my invention can be embodied in various other forms all coming within the scope of the claims which follow.

I claim as my invention:

1. In a deep well turbine pump, the combination of: an impeller shaft having an annular groove therein; a split sleeve surrounding said shaft, the exterior of said sleeve being tapered; a shoulder associated with said sleeve and adapted to fit into said groove when said sleeve is contracted on said shaft; an impeller supported on said sleeve, said impeller having a bore therethrough tapered to fit said sleeve; and means for forcing said impeller on said sleeve to contract said sleeve on said shaft.

2. In a deep well turbine pump, the combination of: an impeller shaft having an annular groove therein; a split sleeve surrounding said shaft, the exterior of said sleeve being tapered divergently downward; a shoulder associated with said sleeve and adapted to fit into said groove when said sleeve is contracted on said shaft; an impeller supported on said sleeve, said impeller having a bore therethrough tapered to fit said sleeve; and a lock-nut threaded on said sleeve, said lock-nut being adapted to force said impeller on said sleeve to contract said sleeve on said shaft and secure it against rotation thereon.

3. In a deep well turbine pump, the combination of: a plurality of bowls, connected together vertically end to end, each bowl having an impeller chamber and passageways connecting the outer portion of said impeller chamber to the central portion of the adjacent upper impeller chamber; a plurality of impellers, one of which is disposed in each impeller chamber; a shaft extending through said impellers; a hub portion extending upward from the upper shroud of each impeller, said hub portion having a bore tapered divergently downward; a sleeve disposed around said shaft in each of said hub portions, the exterior of said sleeve being tapered to fit the tapered bore of said hub portions, said sleeve being split to facilitate the contraction of said sleeve and provide a

- fluid passageway around the upper shroud of each of said impellers; means for forcing said impeller upon said sleeve to prevent its movement relative to said sleeve and to contract said sleeve on said shaft to prevent its rotation relative to said shaft; and means associated with said sleeve and said shaft for securing said sleeve when contracted against axial displacement on said shaft.
4. In a deep well turbine pump, the combination of: a plurality of bowls, connected together vertically end to end, each bowl having an impeller chamber and passageways connecting the outer portion of said impeller chamber to the central portion of the adjacent upper impeller chamber; a plurality of impellers, one of which is disposed in each impeller chamber; a shaft extending through said impellers, said shaft having an annular groove for each impeller bowl; a hub portion extending upward from the upper shroud of each impeller, said hub portion having a bore tapered divergently downward; a sleeve disposed around said shaft in each of said hub portions, the exterior of said sleeve being tapered to fit the tapered bore of said hub portions, there being a slot formed in said sleeve to facilitate the contraction of said sleeve and provide a fluid passageway around the upper shroud of each of said impellers, each of said sleeves having a shoulder adapted to fit into one of said grooves when said sleeve is contracted on said shaft to secure said sleeve against axial movement on said shaft; and a lock-nut adapted to be threaded upon said sleeve to force said impeller downward on said sleeve to secure said impeller against movement relative to said sleeve and to contract said sleeve on said shaft to secure it against movement relative to said shaft.
5. In combination: a shaft; an impeller having a tapered bore therein into which said shaft extends, the walls of said bore diverging in the direction of action of a thrust transmitted to said impeller and tending to move said impeller along said shaft; a split sleeve structure having an external surface tapered to correspond to said tapered bore; and means for preventing axial movement between said sleeve and said shaft whereby the thrust exerted on said impeller moves said sleeve into said bore whereby said sleeve is compressed around the periphery of said shaft.
6. In combination in a deep well turbine pump: a substantially vertical impeller shaft; an impeller having a tapered bore into which said shaft extends, the walls of said bore diverging downward, said impeller being subjected to a downward hydraulic thrust when in operation; a sleeve structure tapered to fit said bore and extending there-
- in; and means adjustable from the top of said impeller for drawing said sleeve structure into said bore in clamping relationship with said shaft.
7. In a deep well turbine pump, the combination of: a shaft; an impeller having a tapered bore and a central passage therein, the smaller end of said tapered bore opening on the top of said impeller and the larger end of said tapered bore opening on said central passage, said shaft extending into said tapered bore; a sleeve structure tapered to fit said bore and providing a lower wall contiguous to the walls of said central passage; and means at the top of said impeller for drawing said sleeve structure into said tapered bore to contract said sleeve structure on said shaft.
8. In a turbine pump, the combination of: a shaft; an impeller providing a central impeller passage through which the pumped fluid passes, said pumped fluid exerting a hydraulic thrust on said impeller; and a clamping means for securing said impeller to said shaft, said clamping means defining a passage communicating between said central impeller passage and a space immediately above said impeller whereby said hydraulic thrust is decreased.
9. A combination as defined in claim 8 in which said clamping means comprises a sleeve closely surrounding said shaft and split longitudinally whereby the space formed by said split defines said passage and permits contraction of said sleeve around said shaft, the external surface of said sleeve being tapered, said impeller providing a bore correspondingly tapered whereby a movement of said impeller along said sleeve contracts said sleeve around said shaft.
10. In combination: a shaft providing an annular groove cut inward from the surface thereof; a split sleeve formed of a single split member contractible to come into surface contact with said surface of said shaft and providing an annular shoulder extending into said annular groove, whereby when said sleeve is contracted said shoulder snugly fits into said annular groove to position said sleeve relative to said shaft but when said sleeve is expanded said annular shoulder moves from said annular groove to permit said sleeve to slide along said shaft, the exterior of said sleeve being tapered; a member having a bore tapered to correspond to the taper of said sleeve and movable into a position around said sleeve after said sleeve is positioned relative to said shaft to effect inter-engagement between said shoulder and said annular groove; and means for moving said member along said sleeve to move said sleeve into contracted position.

ARTHUR R. WEIS.
